UNITED STATES PATENT OFFICE

GUSTAVE L. VOGT, OF PHILADELPHIA, PENNSYLVANIA

SMOKE STICK

Application filed August 7, 1929. Serial No. 384,122.

The present invention relates to smoke sticks.

More specifically, the invention relates to smoke sticks adapted for supporting sausages or Frankfurters within a cage for subjecting them to the action of smoke for curing same against bacteriological action in well known manner.

It is highly important to support the sausages so that the entire surfaces thereof may be subjected to the action of the smoke in the smoke house in order to avoid the commonly experienced light or unsmoked areas on sausages, which in a short time turn dark green. Such areas only reduce the quality of the sausages, and give them a less slightly appearance and accordingly minimize the sale thereof.

Smoke sticks of various constructions have heretofore been provided for supporting sausages within smoke cages but such constructions failed to properly space the links and covered relatively large surface areas of the sausages, which areas were accordingly not subjected to the action of smoke. Accordingly such areas remained uncured and were quite visible in the completed product. This not only affected the sale of the sausages, but to a more or less extent the quality thereof. It is accordingly a primary object of the present invention to provide a smoke stick adapted for supporting sausages within smoke cages whereby substantially the entire surface areas of the sausages are subject to a uniform smoking.

It is a further object of the invention to provide a smoke stick which is relatively simple in construction whereby same is adapted for manufacture at a very low cost.

It is a still further object of the invention to provide a smoke stick of such construction that sausages are capable of being supported thereby and suspended therefrom with a line of contact between the stick and the sausages and whereby the smoke is directed into proximity with the contact points between the sticks and the sausages.

With the above objects in view as well as others that will become apparent during the course of the following disclosure reference

will be had to the accompanying drawing forming part of same, and wherein:

Figure 1 is a side elevational view of a portion of a smoke stick supporting bar forming an integral part of a smoke cage of conventional construction, a plurality of smoke sticks constructed in accordance with the present invention being shown in transverse section in operative association with said bar.

Figure 2 is a fragmentary view indicating the cage bar in transverse section and a portion of one of the smoke sticks associated therewith.

Figure 3 is a transverse sectional view of one of the smoke sticks showing a string of sausages supported thereby for subjecting to the action of smoke.

Referring to the drawing in which like parts are designated by like reference characters, 11 designates a smoke stick constructed in accordance with a preferred embodiment of my invention, and which comprises an angle member which is preferably constructed of galvanized iron, and which, as indicated in Figures 1 and 3, is preferably right angular with the opposite legs thereof equal in length as seen in transverse section. However the bar may be constructed other than right angular if desired. The material of which stick 11 is constructed is relatively thin as represented in Figures 1 and 3 and the free edges of the opposite legs thereof are at right angles to the plane surfaces of the legs, defining sausage contact points indicated at 12 in Figure 3.

The sticks 11 constructed as described are adapted for removable disposition adjacent opposite ends thereof in transversely alined semi-circular notches N in bars B forming parts of conventional smoke cages. The sticks 11 are disposed in alternate transversely alined pairs of notches N as represented in Figure 1 in the same manner as the commonly employed circular wooden sticks are now disposed. It will be seen upon reference to Figure 1 that the angle bar sticks constructed in accordance with the present invention are readily adapted for stable support within the conventional notches N due

to engagement of the apex and opposite side surfaces thereof with the notches as indicated.

In the use of smoke sticks of the character above described a plurality thereof are supported within notches N of the bars B of smoke cages whereupon strings of sausages are supported by each of the sticks 11 as indicated in Figure 3. The strings of sausages are arranged in spaced relation longitudinally of the sticks 11 and by disposing sticks 11 in alternate sets of notches N the strings of sausages supported by adjacent sticks are in spaced relation thus avoiding contacting surfaces which would preclude the action of smoke thereto. The strings of sausages are supported by sticks 11 in the manner indicated in Figure 3 whereby only two sausages of each string thereof contact the stick and by providing the sticks of angular formation as disclosed the two sausages of each string have only a line or point contact as indicated at 12 with stick 11 whereby the surface areas of the sausages are completely exposed and accordingly substantially the entire areas are subjected to uniform smoking action thus avoiding the discolored surface areas commonly seen on sausages now marketed.

Furthermore, the angular stick formation as disclosed provides smoke deflecting walls which deflect smoke which emanates from beneath the sticks into proximity to the sausage contacting points 12 for assuring complete smoking at these points.

While the angle bar sticks are preferably of solid formation as indicated, openings may be provided in the apices thereof for admitting smoke between the outwardly diverging legs thereof, however such openings are not necessary as the smoke will penetrate between the diverging legs from above the upper edges thereof for uniform contact with the entire surfaces of the sausages.

From the foregoing disclosure it will be seen that a smoke stick is provided which is very simple in construction, readily adapted to smoke cages now in use and which will effectively support sausages for the action of smoke to the entire surface thereof.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of the equivalency of the claims are therefore intended to be embraced therein.

What I claim as my invention is:

1. A smoke stick for sausages comprising a unitary angle bar the legs of which are arranged so as to diverge upwardly, providing spaced line contact supports for the links

of sausages and so that the under surface of said angle bar serves to direct smoke toward said lines of contact.

2. A unitary smoke stick in the form of a metallic angle bar of right angular form disposed so that the legs thereof diverge upwardly and so that the ends of the legs present surfaces inclined away from vertical planes passing through the extremities of said legs so that links of sausages suspended vertically from said bar will have a line contact with the ends of said legs toward which vertically moving smoke will be guided by the under divergently-disposed surfaces of said legs.

In testimony whereof I affix my signature.
GUSTAVE L. VOGT.
